VENDING MACHINE EMPTY SIGNAL
INDICATING MECHANISM

Wallace R. Lyman, West Springfield, Mass., assignor to
Westinghouse Electric Corporation, Pittsburgh, Pa., a
corporation of Pennsylvania

Filed Apr. 28, 1965, Ser. No. 451,576
4 Claims. (Cl. 221—6)

This invention relates to vending machines and more
particularly to empty signal mechanisms for vending
machines.

Multi-column vending machines which are adapted to
contain different stacks of articles to be vended in re-
spective different column structures of the machine are
well known. It is of course desirable to provide individual
column empty signal mechanisms and also an all column
empty signal mechanism to indicate a sold out con-
dition of such machine. It is also desirable that such
signal mechanism be as simple, reliable in operation and
inexpensive as possible.

It is the principal object of the present invention to
provide a simple and reliable empty signal mechanism
for a multi-column vending machine that is operable to
individually indicate empty conditions of respective ones
of the vending machine columns and to also indicate
by separate signal means the sold out condition of the
machine when all storage columns of the vending machine
are empty.

In accordance with the invention, a vending machine
magazine frame arranged to have a plurality of side
by side positioned article storage column structures is
provided with a plurality of movable article sensing levers
for each column structure adapted to contact an
article in the respective column to assume a first position
and movable to a second or operated position when the
column is empty and no articles are present and sensed.
In addition a common signal member is movably mounted
on said frame to be interconnected with each of said
article sensing levers to assume a first position when at least
one of said individual column levers is in its first position
and to be moved to assume a second or operated position
when all of said levers are in their second positions. Indi-
vidual column empty signal means is arranged to be
responsive to the operated position of respective ones
of said article sensing levers and in addition an all
empty or sold out signal means is arranged to be re-
sponsive to the operated position of said common sig-
nal member.

In a particular embodiment of the invention, each of
said article sensing levers is pivotally mounted on the
frame to assume a raised position when an article to be
vended is present in the respective column of the
machine and to be moved by gravity to a lowered position
when the respective column is empty. The common
signal member is pivotally mounted on the frame in a
position to bridge all of the individual column article
sensing levers to be thereby supported in a raised position
so long as any one of the article sensing levers is in
the raised position and to be movable to drop by gravity
to a lowered position when all of said article sensing
levers are in their lowered positions.

Further objects, features and the attendant advantages
of the invention will be apparent with reference to the
following specification and drawings, in which:

FIGURE 1 is a perspective elevation of a vending
machine magazine structure having a plurality of side by
side positioned article storage columns together with the
empty signal mechanisms of the invention mounted on
the lower portions of the vending machine magazine;

FIG. 2 is a fragmentary sectional view through the ex-

2

treme left-hand column of the lower end of the magazine
to show details of the article sensing lever; and

FIG. 3 is a fragmentary detail view partly in section
to show the position of an individual column article sens-
ing lever when the associated column is empty.

Referring to FIG. 1 of the drawings the vending ma-
chine magazine structure generally shown at 10 is ar-
ranged to have a plurality of side by side article storing
column structures such as the six columns shown at
11 through 16. It should be understood that the article
sensing and empty signal mechanisms of the invention are
not limited to any particular number of side by side
column structures as will be apparent from the following
description. Each of the article storage columns 11-16
is provided with article vending release mechanisms gen-
erally shown at 17 through 22 and since these release
mechanisms are not a part of the present invention and
a detailed description of them is not required for an
understanding of the present invention, no further de-
scription of the vending release mechanisms will be made.
If a further description of the vending mechanism re-
lease is desired, reference may be made to the copending
patent application of Francis A. Gasperini, Serial No.
451,579, filed April 28, 1965, and assigned to the same
assignee as the present application for patent.

Each of the side by side positioned article storage
columns 11-16 is provided with a respective movable
article sensing lever 31-36 which is adapted to have a first
position such as the raised position shown by the article
sensing lever 31 when an article to be vended is present
in the storage column such as any of the articles 37-39
in column 11. The movable article sensing lever is pivot-
ally mounted on the frame of the vending machine maga-
zine 10 in a position adjacent the lower end of the respec-
tive column structure 11-16 and is movable to a second
or operated position such as the lowered position shown
by any one of the article sensing levers 32-36 when
their respective column structures 12-16 are empty of
articles to be vended.

Referring now to FIG. 2 of the drawings, one of the
empty sensing levers namely the empty sensing lever 31
for the vending column structure 11 will be described
in more detail. It should be understood that all of the
individual column empty signal sensing article sensing
levers 31-36 are identical and therefore the specific de-
scription of the sensing lever 31 will suffice for the rest
of the sensing levers. The sensing lever 31 is essentially
a bell crank pivoted at 40 and having a heel portion 41
adapted to contact the butt end of the article to be vended
such as the can or bottle 37 and a cam surface end 43
adapted to contact the roller 44 of a suitable individual
column empty signal such as the indicator, switch or light
45. Referring more particularly to FIG. 3 of the draw-
ings, when the respective vending machine column is
empty, the heel portion 41a, for example, of the empty
signal lever 32 will not be contacting or sensing an ar-
ticle to be vended and the article sensing lever 32 will
pivot about the pivot 40a to move the cam surface 43a
into engagement with the cam roller 44a and activate the
individual column empty switch or light 45a. By properly
proportioning the weight of the cam end 43 or 43a for
each empty sensing lever such as the lever 31 or 32 in
relation to the heel end 41 or 41a, as will be obvious to
one skilled in the art the respective empty sensing lever
can be caused to pivot about its pivot such as the pivot
40 or 40a in response to the force of gravity when no
article is sensed in the respective article storage column.
However, to assure the pivotal movement of the in-
dividual article column sensing lever, a tension spring 46
may be connected as shown.

Referring now again to FIG. 1 of the drawings, the
common empty signal means is shown to comprise the

ar 50 pivotally mounted at each of its ends, one of which shown at 51 to the frame structure of the vending machine magazine 10. It will be noted that the common signal bar 50 is positioned to bridge all of the individual empty signal levers 31-36 and to be supported in a raised position so long as any one of the individual empty sensing levers 31-36 is in the raised position. Therefore, the common signal means or bar 50 is movable from a first position, i.e., the raised position by the interconnection of any one of the individual column empty sensing levers 1-36. When all of the individual article sensing column empty signal levers 31-36 have moved to their second operated or lowered positions at the time when all of the columns of the vending machine are empty and the machine is sold out, the common signal bar 50 will drop downward by the force of gravity in the direction of the arrow as shown by FIG. 1 to a second position. The downward movement of the common signal bar 50 is connected by a link lever 52 to a sold out switch 53 which is thereby activated when the bar 50 has moved downward in the direction of the arrow to energize the all empty or sold out signal light 54.

In the foregoing, there have been described extremely simple forms of empty signal arrangements for signalling the individual empty conditions of respective ones of a plurality of side by side article storage columns together with the sold out condition of the entire machine when all of the columns are empty. Various modifications will occur to those skilled in the art.

I claim as my invention:

1. A vending machine comprising, a frame having a plurality of side by side column structures adapted to contain articles to be vended, each of said column structures having respective article sensing levers adapted to contact an article in the column and to be movable to assume a first position in response thereto and to assume a second position when no article is present in the respective column, a movable common signal member, means interconnecting each of said article sensing levers and said common signal member to move said common signal member to a first position when at least one of said article sensing levers is in its first position and to move said common signal member to a second position when all of said article sensing levers are in their second positions, a respective individual column empty signal means responsive to a respective one of said article sensing levers to be operated when the respective lever is in a selected one of its said positions, and an all column empty signal means responsive to said common signal member to be operated when said common signal member is in a selected one of its said positions.

2. A vending machine comprising, a frame having a plurality of side by side column structures adapted to contain articles to be vended, each of said column structures having respective article sensing levers adapted to contact an article in the column and to be movable to assume a first position in response thereto and to assume a second position when no article is present in the respective column, a movable common signal member, means interconnecting each of said article sensing levers and said common signal member to move said common signal member to a first position when at least one of said article sensing levers is in its first position and to move said common signal member to a second position when all of said article sensing levers are in their second positions,

5 a respective individual column empty signal adapted to be connected to a respective one of said article sensing levers to be operated when the respective lever is in the second position, and an all column empty signal adapted to be connected to said common signal member to be operated when said common signal member is in the second position.

3. A vending machine comprising, a frame having a plurality of side by side column structures adapted to contain articles to be vended, each of said column structures having respective article sensing levers pivotally mounted on said frame and adapted to contact an article in the column and to be movable to assume a first position in response thereto and to assume a second position when no article is present in the respective column, a movable common signal member pivotally mounted on said frame, means interconnecting each of said article sensing levers and said common signal member to move said common signal member to a first position when at least one of said article sensing levers is in its first position and to move said common signal member to a second position when all of said article sensing levers are in their second positions, a respective individual column empty signal adapted to be connected to a respective one of said article sensing levers to be operated when the respective lever is in the second position, and an all column empty signal adapted to be connected to said common signal member to be operated when said common signal member is in the second position.

30 4. A vending machine comprising, a frame having a plurality of side by side column structures adapted to contain articles to be vended, each of said column structures having respective article sensing levers pivotally mounted on said frame and adapted to contact an article in the column and to be movable to a raised position in response thereto and to a lowered position when no article is present in the respective column, a movable common signal member pivotally mounted on said frame in bridging relation to said article sensing levers, means interconnecting each of said article sensing levers and said common signal member to support said common signal member in a raised position when at least one of said article sensing levers is in a raised position and to allow said common signal member to drop to a lowered position when all of said article sensing levers are in their lowered position, a respective individual column empty signal adapted to be connected to a respective one of said article sensing levers to be operated when the respective lever is in the lowered position, and an all column empty signal adapted to be connected to said common signal member to be operated when said common signal member is in the lowered position.
